5 Claims. (Cl. 139—66)

ABSTRACT OF THE DISCLOSURE

The dobby connector of the present invention is so constructed as to cause most of the stresses created on the connector during the forward stroke of the actuating lever to be absorbed by a bearing surface located between the swivel block and the main portion of the dobby connector, rather than to be absorbed by the swivel pin alone, as is the case in prior art devices.

Background of the invention

This invention is directed to dobby connectors for weaving looms, and more particularly to swiveled dobby connectors, in which the reciprocating action of the dobby knife requires that a portion of the dobby connector swivel.

In the prior art devices, loom dobbies customarily include a pair of oppositely spaced reciprocating knives which cooperate with hooks and are pivotally connected to dobby levers and controlled by a pattern mechanism. The levers in turn are connected to harness jacks which lift corresponding harnesses when the associated hook is moved outwardly by one of the reciprocating knives. The rear harness frames are moved through a greater vertical distance than the forward harness frames, therefore the dobby knives swing from one oblique position to an oppositely disposed oblique position at the end of their working stroke, the greater distance of travel being at the rear end of the knift.

The dobby knives are connected at each of their ends to a dobby connector, which in turn is driven in a reciprocating manner by the actuating levers. During the forward stroke the dobby knife engages the hooks moving them outwardly and thus causing the jacks to raise the harnesses.

When the load on the harnesses is considerably heavy due to an increased shed or heavy warp, the force necessary to raise the harnesses is brought to bear on the pin which connects the pivotal element of the dobby connector with the main body. As can be seen, such heavy stresses will tend to break or shear the pins.

Summary

In the present invention, however, the heavy stresses on the connector pin are alleviated by providing a bearing plate which is engaged by a radial surface of one end of a swivel block in the dobby connector. During the thrust stroke of the actuating levers the force which is normally taken up solely by the connector pin is primarily absorbed by the bearing plate, and thus the stresses are distributed over the bearing surface as a compressive force, rather than a shear force on the connector pin.

It is therefore an object of this invention to provide a dobby connector in which the pressures brought to bear on the connector pin are transferred and primarily absorbed by a separate bearing plate without affecting the pivotal movement of the swivel block.

Another object of this invention is to provide a device of the character described which may replace existing dobby connectors and when installed on present looms is completely compatible with the other dobby elements. The improved connector can be installed at a nominal cost.

2

A still further object of this invention is to provide a means for preventing the breaking or shearing of connector pins by providing a compressive bearing surface to absorb a portion of the stress normally received solely by the connecting pin.

With these and other objects in view which will appear as the description proceeds, my invention resides in the combination and arrangement of parts hereinafter described and set forth.

In the accompanying drawings:

FIGURE 1 is a front elevation of a dobby with parts broken away illustrating upper and lower dobby connectors made according to the present invention;

FIGURE 2 is a plan view of the dobby shown in FIGURE 1, and showing the angular disposition of the knives at the ends of their reciprocating strokes;

FIGURE 3 is an enlarged perspective view of the assembled dobby connector removed from the loom;

FIGURE 4 is an exploded perspective view of the dobby connector; and

FIGURE 5 is a perspective view of the bearing plate looking at the other end from that shown in FIGURE 4.

Description of the preferred embodiment

Referring now to the drawings, FIGURES 1 and 2 are environmental views showing the dobby connector 10 in use on a dobby D. The actuating lever L is set in motion and transmits a reciprocating force to the dobby connector 10 through the connecting rod C. The knife K is connected at each end to a dobby connector 10, and reciprocates with the corresponding movement of the dobby connector. According to the desired pattern, the knife K engages and pulls forward a hook H, thus actuating the corresponding jack J to either raise or lower the corresponding harness.

The above description is standard in the weaving art, and forms no part of the invention, but is explanatory of the environment in which my invention resides and illustrates the problem solved by the invention.

The reciprocating motion of the knife K, as explained above, requires at least a portion of the dobby connector 10 to be pivotal. Also, during the outward thrust of the knife K, all of the force necessary to move the knife blade K and thus raise the harnesses is brought to bear on a single pin 50 through each dobby connector. This results in extreme stress on the connector pin 50 and usually results in short life for the pin. According to the invention this stress is eliminated from the connector pin and transmitted through a bearing surface located adjacent the pivotal portion of the dobby connector.

The present invention is more clearly specified in FIGURES 3 and 4, wherein it is shown that the dobby connector 10 includes a stationary block member 11, preferably formed of a high molecular weight polyethylene, and said block 11 having a portion thereof bifurcated to form a base portion 12 and a pair of longitudinally extending ears 14 and 16 extending from one end thereof. Base portion 12 is provided with a longitudinal passageway 18 extending completely through the base portion 12 of block 11 and emerging between ears 14 and 16. The ears 14 and 16 are provided with aligned transverse openings 20 and 22.

A metallic bearing plate 30 comprises a plate 36 with a tubular portion 32 projecting from one side thereof which is adapted to extend into passageway 18 of block 11. The tubular portion 32 has its inner surface 34 threaded to provide a means for receiving one end of the connector arm C in FIGURE 1, said arm C connected at its other end to the actuating lever L. The diameter of passageway 18 and the outer surface of tubular portion 32 are so dimensioned as to fit snugly together when the bearing plate 30 is in its assembled position.

The other side of plate 36 is machined to form a radially recessed bearing surface 38 in the bearing plate 36. The bearing surface 38 is preferably formed as to extend transversely of the passageway 18 and parallel with the axis of openings 20 and 22 in the ears 14 and 16.

Swivel block 40 is also formed of high molecular weight polyethylene and comprises a shaped block 41 which is curved at one end as at 42 to conform with the bearing surface 38 in bearing plate 30. This curved portion 42 in the assembled position bears against bearing surface 38 and is adapted to pivot within bearing surface 38 in cooperation with the motion of the knife as to be herein-after described.

Swivel block 42 is also provided with a first transverse passageway 44 and, when assembled, is aligned with openings 20 and 22 in the block 11. Pivot block 40 is provided with a second passageway 46 transverse to passageway 44 and also transverse to passageway 18, and is adapted to receive one end of the knife assembly K. Since one end of the knife assembly K reciprocates through a longer stroke than the other end, it is necessary for the swivel block 40 to pivot slightly within the stationary block 11 of the dobby connector 10, following the action of the reciprocating knife.

Bearing pin 50 comprises a cylindrical portion 52 which extends through passageways 20, 44, and 22 to maintain the swivel block 40 in assembled relationship to stationary block 11. A shoulder 54 at one end of pin 50 bears against the outer surface of one of the ears 16 in stationary block 11. The other end of the cylindrical portion 52 is provided with a radial bore 56 through which a fastening or cotter pin 60 extends to hold the pin 50 in the passageways 20, 22 and 44.

In the assembled position, swivel block 40 is held in bearing relationship against bearing plate 30 by pin 50. As the pivot block 40 pivots slightly within recess 32 as a result of the action of the knives K, this bearing relationship is maintained, and thus during the thrust stroke of the actuating lever, most of the stresses caused by the action of the harness springs and the weight of the harness frames and warp and normally taken up by the prior art bearing pins are now absorbed by bearing plate 30. Of course, during the return stroke all of the stress is brought to bear on the bearing pin 50, however, this is negligible.

Having thus described my invention it will be seen that changes and modifications may be made therein by those skilled in the art without departing from the spirit and scope of the invention, and I do not wish to be limited to the details herein disclosed, the scope of the invention being defined in the following claims.

I claim:

1. In a dobby connector adapted to transmit force between an actuating lever and a knife blade, said actuating lever creating a reciprocal linear movement to said dobby connector which is thereby transmitted to said knife blade, said dobby connector comprising:

(a) a main body having means on one end for receiving a connecting rod from said actuating lever, said

main body having a bifurcated portion forming two longitudinally extending parallel ears at the other end thereof;

- 5 (b) a swivel block pivotally positioned between the inner surfaces of the parallel ears and having means therein for receiving one end of said knife blade along an axis generally perpendicular to the axis of linear motion of said dobby connector, and said swivel block pivoting slightly in response to the action of said knife blade; and
- 10 (c) a bearing block positioned between the inner surfaces of said parallel ears and secured between the swivel block and said main body in bearing relationship to said swivel block, said bearing block absorbing the force transmitted by said actuating lever in its thrust movement.

2. The dobby connector according to claim 1 wherein one side of said bearing block is provided with a radially recessed bearing surface, one end of the swivel block being provided with a radial surface contiguous with the recess in said bearing block, said recess in the bearing block receiving the radial surface of the swivel block, said swivel block and said bearing block being maintained in a bearing relation to each other during the thrust stroke 25 of the actuating lever.

3. The dobby connector according to claim 2 wherein each of the parallel ears are provided with an opening transverse to the longitudinal axis of said knife blade, said swivel block being provided with a first passageway 30 aligned with the openings in said parallel ears, and a pin extending through said passageway in the swivel block and said openings in the ears to maintain them in a secure position.

4. The dobby connector according to claim 3 wherein 35 the means for receiving said connecting rod comprise a tubular portion extending from the side of the bearing block opposite the cylindrical recess along the axis of longitudinal motion of the dobby connector, a passageway in the main body of the dobby connector extending 40 along said axis of longitudinal motion, said passageway receiving said tubular portion to retain said bearing plate in said main body portion said tubular portion having an interior surface which receives said connecting rod.

5. The dobby connector according to claim 4 wherein 45 said main body and said swivel block are formed of high molecular weight polyethylene, and said bearing block is metallic.
